CLAIM

The ornamental design for a wearable device with animated graphical user interface, as shown and described.

DESCRIPTION

The file of this patent contains at least one drawing/photograph executed in color. Copies of this patent with color drawings(s)/photograph(s) will be provided by the Office upon request and payment of the necessary fee.

FIG. 1 is a front view of a wearable device with animated graphical user interface showing a first image of the claimed design;

FIG. 2 is a second image thereof;

FIG. 3 is a third image thereof; and

FIG. 4 is a fourth image thereof.

FIG. 5 is a front view of another embodiment of a wearable device with animated graphical user interface showing a first image of the claimed design;

FIG. 6 is a second image thereof;

FIG. 7 is a third image thereof; and

FIG. 8 is a fourth image thereof; and,

FIG. 9 shows an environmental wearable device to which the designs of FIGS. 1-4 and FIGS. 5-8 may be applied.

The broken lines in FIGS. 1-8 show a display screen and a wearable device having a display screen, and form no part of the claimed design.

The appearance of the animated image sequentially transitions between the images shown in FIGS. 1-4 and FIGS. 5-8, respectively. The process or period in which one image transitions to another forms no part of the claimed design.
